UNITED STATES PATENT OFFICE.

WILLIAM R. ALLEN, OF CLEVELAND, OHIO, ASSIGNOR TO THE AMERICAN MULTIGRAPH COMPANY, OF CLEVELAND, OHIO, A CORPORATION OF OHIO.

RETAINING-CLIP FOR TYPE OR PRINTING-PLATES.

1,274,363.

Specification of Letters Patent.

Patented Aug. 6, 1918.

Application filed May 19, 1917. Serial No. 169,626.

To all whom it may concern:

Be it known that I, WILLIAM R. ALLEN, a citizen of the United States, residing at Cleveland, in the county of Cuyahoga and State of Ohio, have invented a certain new and useful Improvement in Retaining-Clips for Type or Printing-Plates, of which the following is a full, clear, and exact description, reference being had to the accompanying drawings.

This invention relates to a spring clip adapted to hold type or printing plates on a suitable holder having parallel rails. The invention is in the nature of an improvement on the clips shown in Patents Nos. 1,031,447 and 1,031,661 granted July 2nd, 1916, to The American Multigraph Company, as assignee of Ferdinand Hohenberger and Henry C. Osborn, respectively. The present clip is believed to be dominated by the claims of each of those patents.

As shown in the patents referred to the clip is made of a single piece of sheet metal bent intermediately to produce a hollow overhanging head from the under side of which the end portion of the metal projects downwardly in the form of outwardly convex wings. Such a clip may be sprung between the heads of adjacent rails, and, by binding against them, hold type located between the rails against longitudinal shifting. In the latter patent above referred to, the head is provided with a projecting lip at one end, which may overhang the flange of a printing plate so that the clip may serve both to hold a plate resting on the tops of the rails and to prevent shifting of grooved type slidably mounted between the rails.

The clips shown in the patents referred to have been found satisfactory in practice where the rails on the type-holding member are accurately equidistant, as is desirable. However, it has been found difficult to obtain rails of exactly the same width of head, and it is also difficult to mount them accurately spaced on a segment or drum-like holder. Accordingly, it frequently happens that the holders do not have the type channels of absolutely equal dimensions, with the result that if the clip is properly dimensioned to effectively engage the rails where the channel is widest, such clip, when inserted between narrower channels, will have the free ends of the wings impinge each

other and the shape of the wings thereby distorted as they are inserted. This causes a permanent set in the spring metal and interferes with the subsequent use of the clip. The present invention is designed specifically to overcome this difficulty and provide a clip equally adapted for use in channels of varying size, within a range which may be easily maintained in the manufacture of type-holding drums or segments.

In accomplishing the above object, I have recessed one of the wings of the clip intermediately and have removed the end portions of the other wing, so that the latter wing is adapted to extend through the recess of the former wing. In such a clip the free edges of the wings do not constitute positive stops limiting the inward movement, and a much wider range of movement is allowed than in the clips shown in the patents mentioned.

My invention is illustrated in the drawings hereof and is hereinafter more fully explained, and its essential characteristics are summarized in the claims.

In the drawings Figure 1 is a perspective view of my clip; Fig. 2 is a side elevation of the same; Fig. 3 is a fragmentary cross section through a type-holding segment, carrying type and a printing plate and using my holding clips; Fig. 4 is an enlarged section through adjacent rails showing a clip in place in end elevation; Fig. 5 is a plan of a portion of a type holder equipped with my clips and showing their use in holding type and printing plates; Fig. 6 is an enlarged diagrammatic view illustrating the extreme inward position of the clip wings.

10 represents the clip complete. As shown, it consists of a sheet metal member having an intermediate substantially flat portion 11 at the edges of which the metal rounds downwardly, as at 12, and then inwardly, as at 13, to position each side of the longitudinal central plane. From these positions the end portions of the metal are turned downwardly 14 and 15.

The wing 14 of my clip is intermediately recessed, as shown at 16, the recess being conveniently of a segmental form. The wing 15 has its corners 17 removed, preferably on a curve, so that the extreme edge 18 of the remaining portion of this wing is con-

siderably smaller than the length of the recess 16. This recessing of one wing and removing the corners of the other allows one wing to move through the other, to a certain extent, thus increasing the possibility of approach of the wings and preventing the convexities being distorted when the narrowness of the channel springs them inwardly beyond the normal. This positive overlap-

10 ping of the wing edges is clearly illustrated in Fig. 6.

In Fig. 3, A indicates a suitable type-holding drum or segment carrying radial rails B. These rails, as shown, in this figure and in Fig. 4, have overhanging heads b, whereby undercut longitudinal channels are provided adapted to confine grooved type. The type may be of the character shown in Patent No. 836,026, granted November 13, 20 1906, to The American Multigraph Company, as assignee of Harry C. Gammeter. Such grooved type are illustrated in Figs. 3 and 5 hereof at C, these type being prevented from shifting longitudinally by abutting 25 the ends of the clips. These views also show at D a printing plate resting on the tops of the rails, this plate being held by lips 19 projecting from the end of the top portion 11 of the clip.

30 After the type are in place between the rails, or after the plate has been put in place, the locking of these printing members is effected by pressing the clip radially inward so that its wings spring into channels, and then, if necessary, shoving the clip lengthwise by a considerable pressure. In this inward radial movement of the wings the free edges thereof are necessarily brought toward each other as the crowns of 35 the wings pass between the rail heads. With rails positioned to carry type of pica size, for instance, the space between the rail heads is so small that the necessary convexity of the clip wings required to obtain 40 a firm hold on the rail heads, brings the inner edges of the free edges of the wings into substantially the same plane when the wings are passing between the rail heads. Accordingly, it results, in the old construction, that if the rail heads are slightly too 45 close together the free edges of the wings abut and form a positive stop, and the sides of the wings are flattened out by the insertion and take a permanent set in such 50 flattened form, so that the clip does not operate satisfactorily when thereafter employed in a channel of normal width or one slightly greater than normal. The present invention avoids this, as it lets each wing 55 spring inward freely considerably past the other, as clearly illustrated in Fig. 6.

Having thus described my invention, what I claim is:

1. A spring clip comprising a head and 65 two projecting wings which are bowed out-

wardly, said wings having their edge portions formed into a coöperating recess and a projection respectively, whereby their free edges may move beyond the plane between the wings.

70

2. A spring clip having a head and two longitudinal wings which extend from the side edges of the head and are bowed outwardly, one of the wings having a recess extending from its free edge and the other wing having a reduced portion adapted to extend laterally through such recess.

75

3. A spring clip having a head and two projecting outwardly bowed wings adapted to engage rail heads, said wings being so formed that their free edges may be moved each past the other.

80

4. A spring clip having a head and two wings side by side, one wing having an intermediately positioned recess extending from its extreme edge toward the head, the other wing having its corners removed to points overlapping the recess.

85

5. A spring clip made of a single piece of sheet metal bent to produce a head and two outwardly bowed projecting wings, said wings being complementarily cut away at their edges, whereby each may be moved past the other.

90

6. A spring clip made of a piece of sheet metal bent to make an intermediate substantially flat head with in-curved edges, and two projecting longitudinal outwardly bowed wings side by side extending from the inner edges of the in-curved portions of the head, one wing being provided with a projection and the other with a recess, which recess and projection are located opposite each other.

95

7. A spring clip having a head and two wings side by side and bowed outwardly, one wing having an intermediately positioned recess extending from its extreme edge toward the head, the other wing having its corners removed to points overlapping the recess, the recess being segmental and the corners of the other wing being removed on curves.

100

8. A spring clip made of a single piece of metal bent to make an intermediate head, and two projecting longitudinal wings side by side, which wings are bowed outwardly in straight lines, one wing having a centrally located long recess extending from its free edge upwardly, and the other wing having its corners removed to points overhanging the recess, whereby the extreme edges of the wings may be forced to opposite sides of the intermediate plane between the wings proper.

110

9. A spring clip for use between a pair of parallel type-holding rails, said clip being made of a single piece of sheet metal having a flat intermediate portion with rounded edges, two inwardly projecting portions

115

120

125

130

substantially parallel to the flat portion and spaced therefrom, and two wings projecting from the inner edges of the inwardly projecting portions, said wings being outwardly bowed while being longitudinally straight, one of said wings having a central recess and the corners of the other wing

being removed to points overlapping the recess, whereby the free edge of one wing may be caused to overlap the free edge of 10 the other wing.

In testimony whereof I hereunto affix my signature.

WILLIAM R. ALLEN.
